UNITED STATES PATENT OFFICE.

ZACHARIAS S. OPPENHEIMER, OF NEW YORK, N. Y.

BOX MEMBER AND BLANK THEREFOR.

Application filed August 22, 1924. Serial No. 733,541.

To all whom it may concern:

Be it known that I, ZACHARIAS S. OPPENHEIMER, citizen of the United States, residing at New York, in the county of New York and State of New York, have invented new and useful Improvements in Box Members and Blanks Therefor, of which the following is a specification.

This invention relates to a box member constructed as set forth by Letters Patent of the United States, No. 1,174,417, granted March 7, 1916, to Ellon S. Hill.

Said patent discloses a flat blank having longitudinal creases near two opposite edges, defining the bases of two longitudinal flanges, and slots at the opposite ends of said creases, defining the inner edges of reinforcing tongues and the ends of two lateral flanges, the blank being also creased to define the bases of said lateral flanges, the longitudinal flanges and tongues being provided with reinforcing strips connecting said flanges with the tongues. In forming a box from said blank the flanges are bent inwardly from the bottom portion of the blank, and the tongues are bent to lie against the inner sides of the lateral flanges. Each flange is of greater width than the said tongues, and is creased longitudinally to define the bases of flaps which are bent inwardly and cemented to the flanges to cover said tongues and reinforcing strips, the said flanges, flaps, and strips forming in the completed box member a laminated wall, the corners of which are strengthened or stayed by the reinforcing strips.

The present invention has for its object to increase the effectiveness of the said reinforcing strips as a corner-strengthening or staying means, and is embodied in the improvements hereinafter described and pointed out in the appended claim.

Of the accompanying drawings forming a part of this specification—

Figure 1 is a side view, showing my improved blank as prepared for erection or setting up to form a box member.

Figures 2, 3 and 4 are fragmentary perspective views, illustrating the operation of setting up the blank to form a box member.

Figure 5 is an enlarged section on line 5—5 of Figure 4.

Figure 6 shows the blank from which the improved reinforcing strip may be formed.

Figure 7 is a side view of a tube formed from the blank shown by Figure 6.

Figure 8 is an end view of the tube.

Figure 9 is an enlarged side view, and Figure 10 an enlarged end view showing the tube flattened.

The same reference characters indicate the same parts in all of the figures.

The blank comprises a body portion 12, two longitudinal flanges 13, and two lateral flanges 14, said blank and flanges being integral and made from boxboard or other suitable material. The blank is provided with longitudinal creases 15 defining the bases of the flanges 13 and with lateral creases 16 defining the bases of the flanges 14.

The blank is provided at opposite ends with slots 17 defining the ends of the lateral flanges 14 and the inner edges of reinforcing tongues 18 which constitute extensions of the longitudinal flanges 13.

The flanges are widened and are centrally creased lengthwise at 20 to define the bases of longitudinal flaps 13^a on the flanges 13, 80 and transverse flaps 14^a on the flanges 14.

The construction thus far described is substantially the same as shown by the Hill patent above mentioned. The blank disclosed by the Hill patent is provided with reinforcing strips or corner stays of thin and strong Kraft paper, said strips extending across the lines on which the tongues 18 are bent, said lines being continuations of the creases 16. According to the disclosure of the Hill patent, each of the reinforcing strips is a single thickness of paper. Said strips are cemented to the flaps 13 and tongues 18. In the completed box, the flaps 13^a and 14^a are folded over and cemented to 95 the reinforcing strips. Said single thickness strips are therefore coated at both sides with cement, which permeates or sinks into the fibers of the strips. The hardening of the cement renders the strips undesirably rigid and brittle and thus detracts from their toughness, a single thickness paper strip permeated by dried cement being more easily torn than one which is free from cement and in its natural condition, of flexibility and toughness. The blank of my invention is distinguished from that above described by the construction of the reinforcing strips or corner stays next described.

Each reinforcing strip is made from a 110

blank 19 of thin sheet material, preferably Kraft paper, the form of the blank being preferably rhomboidal as shown by Figure 6. The blank is wound on a rod or mandrel 5 to form a tube 19^a, as shown by Figures 7 and 8, the tube including a plurality of convolutions as best shown by Figure 8, which shows the tube and the thickness of the paper much enlarged, the thickness of the 10 paper being considerably greater in proportion to the diameter of the tube than in actual practice. When a rhomboidal blank is employed, the blank is wound helically and the inner convolutions are overlapped 15 by the succeeding convolutions in such manner that any cross section of the tube is formed by a plurality of superimposed convolutions (Figure 8). There may be any desired number of these convolutions, four 20 being shown by Figure 8, and two by Figure 10. In forming the tube, the convolutions are left unattached to each other. After the tube is removed from the mandrel, it is flattened as shown by Figures 9 and 10, 25 and is thus converted into a laminated flat sided strip having inner and outer surface layers 21 and intermediate layers 22. The strip as a whole is designated by 19^b. The inner surface layers are cemented to the 30 inner surfaces of the longitudinal flanges 13 and the inner surfaces of the tongues 18, when the blank is flat.

The blank is now ready to be erected or set up to form a box member, as described 35 by the Hill patent. The flaps 13^a are first folded over upon and cemented to the flanges 13 and portions of the outer surface layers 21 of the reinforcing strip, as shown by Figure 2. The flanges 13 are then turned 40 upward and the tongues 18 inward as shown by Figure 3, this operation bending the reinforcing strips into angular form. Finally the transverse flanges 14 are bent upward 45 against the tongues 18, and the flaps 14^a are folded over and cemented to the tongues 18 and the portions of the reinforcing strips thereon, as shown by Figure 4, the flaps 14^a being at the same time cemented to the portions of the flanges 14 not covered by the 50 tongues.

It will now be seen that the surface layers 21 are the only portions of the reinforcing strip which are affected by the cement, and that the intermediate layers 22 are free from 55 cement and retain the original flexibility and toughness of freedom from brittleness of the material of the strip. The inter-

mediate layers therefore constitute substantial relatively tough and flexible parts of the reinforcing strip, and prevent liability of 60 tearing or breakage at the corners of the box member.

The described reinforcing strips may be conveniently manufactured by winding a Kraft paper tube of indeterminate length, 65 flattening it and cutting it into lengths, each sufficient for one reinforcing strip. The winding and flattening operations may be expeditiously performed by simple mechanical means, and the flattening operation 70 renders the final form of the strip sufficiently permanent to permit the application of the strip without any folding operation, excepting that which originally forms the strip.

It will be seen that the reinforcing strips 75 do not overlap the flaps 13^a of the longitudinal flanges, and are characterized by the fact that, each strip is a flattened laminated tube having surface layers 21 contacting 80 with the cement along their entire length and intermediate layers 22 covered by the surface layers, so that the intermediate layers 85 are not rendered brittle by the cement, and are free from each other and from the surface layers.

I claim:

A box member comprising a blank which includes longitudinal and lateral flanges, longitudinal and lateral flaps on said flanges, and tongues at the ends of the longitudinal flanges, the corners of the blank having recesses; and reinforcing strips cemented to the inner sides of the longitudinal flanges and the tongues, the longitudinal flaps being folded and cemented to the longitudinal flanges and to surfaces of the reinforcing strips, the tongues being bent inward so that the reinforcing strips are bent into angular form, the transverse flanges being bent upward against the tongues, and the transverse flaps being folded inward and cemented to the transverse flanges and the reinforcing strips, said strips being characterized by the fact that each strip is a flattened laminated tube having surface layers 90 contacting with the cement along their entire length, and intermediate layers covered by the surface layers, so that the intermediate layers are not rendered brittle by the cement and are free from each other and from the surface layers.

In testimony whereof I have affixed my signature.

ZACHARIAS S. OPPENHEIMER.
